PROCESS FOR THE DISTILLATION OF A MULTICOMPONENT MIXTURE

Frederik J. Zuiderweg, Amsterdam, Netherlands, assignor to Shell Development Company, New York, N.Y., a corporation of Delaware

Application April 10, 1957, Serial No. 652,049

Claims priority, application Netherlands May 24, 1956

5 Claims. (Cl. 208—347)

The invention relates to a process for controlling a distillation process in which a multi-component mixture is continuously distilled in a main distillation zone whereby the final boiling point of one or more products is continuously determined according to the so-called A.S.T.M. distillation method of such a mixture.

In the distillation of multi-component mixtures, e.g., hydrocarbon mixtures such as crude oil and fractions thereof, and particularly in distilling off lighter hydrocarbons such as gasoline, naphtha, kerosene and gas oil, the standardized A.S.T.M. distillation method is usually employed in practice as the specification method for the volatility limits of the distillates produced. With this method the final boiling point of the product obtained is, inter alia, determined. In the assessment of the separation by means of distillation this temperature is very important. It is also important to be able to supply continuously a product of which the final boiling point always has a constant or practically constant value.

There is no direct correlation between the top temperature of the distillation column in which the mixture is treated and the final boiling point of the distillate of this column. The top temperature of the column which is usually measured cannot therefore be used as a measure of the final boiling point, so that it is usually necessary to repeat the A.S.T.M. method (which is a batchwise distillation) continuously at short intervals in order to be sure that the distillate from the column shows no variations. The same applies also to a side stream of the distillation column.

It is an object of this invention to provide a process whereby the final boiling point of a product of a fractional distillation or of the magnitude of a property directly correlated therewith is continuously measured, rendering it unnecessary to continually repeat the batchwise A.S.T.M. method. It is a further object of this invention to use this final boiling point or correlated magnitude to control the distillation of the mixture in the main column in such a way that a product having a constant or approximately constant final boiling point is obtained.

These objects are attained by continuously passing a portion of the distillate or of a side stream of the main distillation column in liquid form into the top part of an auxiliary distillation column, the bottom of which is heated in such a way that the whole quantity of liquid introduced is evaporated and leaves the top of the auxiliary column in the form of vapor (except for small quantities of contaminations which do not evaporate, or only with difficulty); the temperature is then measured at a point between the top and bottom of the auxiliary column, and by means of this temperature one or more

2

of the variables of the distillation process in the main column are controlled in such a way that the temperature measured shows, a constant, or approximately constant value.

5 The auxiliary column used usually has a theoretical tray number of approximately 4 or higher, preferably 6-8.

The ratio between the quantity of mixture present in the auxiliary column and the quantity of liquid supplied 10 to the column per unit of time is kept relatively low; preferably it does not exceed the value of 5 (expressed in minutes). In the latter case an indication of changes occurring in the main column is obtained within 5 minutes.

15 According to the invention there is a specific point between the top and bottom of the auxiliary column where the temperature measured is equal or approximately equal to the final boiling point of the distillate or side stream being controlled, as determined by the so-called

20 A.S.T.M. distillation method. The exact place for this point can be found by calibration. Once this point has been determined the said final boiling point for each mixture introduced into the auxiliary column can be immediately read off. In this way this final boiling point 25 can be continuously determined. In the present control method this point, corresponding to the final boiling point of the mixture being controlled, is preferably selected as the measuring point of the temperature in the auxiliary column.

30 The invention is generally applicable to multi-component mixtures such as hydrocarbon mixtures, mixtures of chlorinated hydrocarbons, alcohol mixtures, mixtures obtained in synthesis processes such as the Fischer-Tropsch process, etc. The method is particularly suitable 35 for the above-mentioned mixtures of lighter hydrocarbons.

The invention will now be described in greater detail with reference to the drawing in which the sole figure is a schematic representation of a process for the control 40 of a continuous distillation of a hydrocarbon mixture.

In the column 1, which is equipped with a plurality of trays, the feed is introduced approximately half-way up via a line 2. At the top, gasoline in vapor form is drawn off at 3 and is condensed in a condenser 4. The 45 gasoline may be separated in a separator 5 from any water which may have distilled over. The water is drawn off at the bottom part of the separator, while gases may be drawn off from the top. The gasoline product which is obtained is led through a line 6 to a storage tank, not shown in the drawing. A portion of the gasoline is 50 recycled to column 1 as reflux.

Heavier hydrocarbon fractions, such as kerosene and gas oil, may be taken from the column 1 at 7 and 8 as 55 side streams. These streams, preferably after heating by heat exchange with the hot bottom product of column 1, may be led to strippers and there stripped from their lightest components by means of steam and/or reboiling; the resultant vapors are again introduced into column 1 at a suitable point. This procedure is shown in the drawing in connection with side stream 7. This stream is led via a heat exchanger 9 to stripper 10 which is equipped with reboiling means. The vapors formed are 60 recycled to column 1 via a line 11. The bottom product of the stripper is withdrawn through a line 12.

Heat is supplied by means of a reboiler 13 to the bottom part of column 1 and steam is introduced through line 14. The liquid bottom product of column 1 is

kerosene fractions with different boiling ranges. The quantity of liquid continuously introduced into the auxiliary column varied between 0.8 and 1.9 litres per hour.

Table

[Temperatures in ° C.]

Final boiling point, A.S.T.M.	84	101	107	110	111	135	137	142	155	164	237	301
Initial boiling point, A.S.T.M.	57	81	73	65	80	76	80	77	46	57	132	220
Boiling range.....	27	20	34	45	31	59	57	65	109	107	155	21
Temperature measured according to invention.....	85	98	106	110	110	136	138	138	158	168	280	340

passed off through a line 15 and withdrawn via the heat exchanger 9.

According to the invention, a small portion of the condensed distillate is continuously introduced into the top part of an auxiliary column 16. This auxiliary column may, for example, be a distillation column of the Vigreux type with a length of 110 cm. and a diameter of 2.5 cm. The column is heated at the bottom part so that all liquid evaporates. The heating may be effected, for example, electrically, as shown in the drawing, or it can be accomplished in other ways as, for instance, by means of the hot residue from the main column. The vapors leave the top of the auxiliary column through a line 17 and may be cooled and condensed to liquid outside the column. A further line with a valve (not shown in the drawing) is provided on the bottom part of the auxiliary column in order to afford the possibility of drawing off at various times heavy components which cannot be evaporated or are evaporated only with difficulty. Such components, e.g. polymeric products, are substantially absent in the top product. The temperature inside the column is measured at a point 18 between the top and bottom of the auxiliary column 16. The temperature value measured is transmitted to a temperature controller 19 which automatically controls in a known manner one of the variables of the distillation process in the main column 1 in such a way that the temperature measured at 18 shows a constant or substantially constant value. The degree of reboiling is shown in the drawing as the variable of the distillation process; thus, temperature controller reduces the degree of heat supplied to the reboiler 13 when the temperature at 18 shows a tendency to rise, and the heat supply is increased when this temperature begins to fall.

The temperature controller could, however, have affected another variable just as well, e.g. the reflux of column 1; in this case the quantity of reflux should increase as the temperature measured increases, and decrease as the temperature decreases. The temperature controller may also be made to affect more than one variable at the same time. Moreover, instead of the distillate, a portion of one of the side streams of the main column could have been led into the auxiliary column.

The temperature measured at 18 is correlated with the final boiling point determined according to the A.S.T.M. distillation method. It is, however, possible to indicate a point in the auxiliary column 16 at which the temperature is equal or almost equal to this final boiling point. This temperature is preferably used for controlling the main column. In the above-mentioned embodiment of the auxiliary column this point was 5 cm. above the bottom of the column. The agreement between the temperature measured at this point of the column and the final boiling point determined according to the A.S.T.M. distillation method is shown by the following tests which were carried out with twelve gasoline and

15 The table includes the values of the final boiling point and the initial boiling point, both determined by the A.S.T.M. distillation method, as well as the boiling range and the temperature measured in the manner according to the invention. It follows from these values that with the use of the present process the final boiling point 20 according to the A.S.T.M. method can, in fact, be determined continuously.

I claim as my invention:

1. A method of controlling a fractional distillation process wherein a multi-component feed is evaporated 25 in a main vertical distillation zone and various relatively narrow fractions of the feed are withdrawn from different parts of said main distillation zone, the heavier fractions being withdrawn toward the bottom and the lighter fractions toward the top, which comprises transferring a small 30 portion of a fraction in liquid form from said main distillation zone to the top of a relatively small auxiliary vertical distillation zone, supplying heat at the bottom of said auxiliary zone such that substantially all of said portion is evaporated as it passes downward in said auxiliary zone and the vapors therefrom rise up through downcoming liquid in said auxiliary zone, and using the temperature at one point intermediate the top and bottom of said auxiliary zone at which point the highest 35 boiling fractions are vaporizing to control at least one of the variables relating to the thermal balance of said fractional distillation process such that the final boiling point of said fraction is determined according to a predetermined correlation between said temperature and said final boiling point.

40 2. The method of claim 1 wherein the point of the auxiliary distillation zone at which the temperature is used as a control is determined such that said temperature is approximately equal to the final boiling point of said fraction being controlled.

45 3. The method of claim 1 wherein the multi-component feed is a hydrocarbon mixture obtained from a crude oil.

50 4. The method of claim 1 wherein the vapors leaving the top of the main distillation zone is condensed and a 55 portion of the condensate is the liquid which is evaporated in the auxiliary zone in order to control the final boiling point of said vapors.

55 5. The method of claim 3 wherein gasoline vapors leaving the top of the main distillation zone are condensed and a portion of the resulting gasoline is transferred to the auxiliary zone in order to control the final boiling point of said gasoline.
